United States Patent Office.

FREDERICK SHALLER, OF HUDSON, NEW YORK.

Letters Patent No. 83,886, dated November 10, 1868.

IMPROVEMENT IN GAS-BURNER ATTACHMENT.

The Schedule referred to in these Letters Patent and making part of the same.

Be it known that I, FREDERICK SHALLER, of the city of Hudson, in the county of Columbia, and State of New York, have invented a new and useful Attachment for Gas-Burners; and I do hereby declare that the following is a full, clear, and exact description of the construction and operation of the same, reference being had to the annexed drawings, making part of this specification, in which—

Figure 1 is a side elevation of the attachment, as it appears when in use.

Figure 2, a perspective view of same, when attached to the burner by a metallic plate-spring.

Figure 3, a perspective view, when it is attached to burner by a wire spring.

Figure 4, a view of plate-spring detached from burner.

Figure 5, a view of wire spring detached from burner.

Like letters indicate like parts in all the figures.

The design of this attachment is to increase the volume of flame of the ordinary gas-burner, for the use of jewellers, dentists, and others who employ the blow-pipe for soldering or other purposes where a large flame is required. This device also increases the illuminating and the heating-power of the burner, without increasing the consumption of gas.

The gas-burner best adapted to this attachment is that having circular holes or apertures for the emission of the gas. The slotted or fish-tail burner is not so good for the purpose when the flame is to be used for soldering.

To enable those skilled in the art to make and use my invention, I will proceed to describe its construction and operation.

Upon a circle of wire, from one inch and a half to two inches in diameter, I build up a low cone or cap, A, of fine wire, by winding it to a thickness sufficient to retard the flame as it issues from the burner, but not so thick as to be impervious to it.

This cap or cone of fine wire is mounted on a wire or other metallic support, b, which is itself supported and embraced by a flat metallic spring, c, which clasps the base of the burner B, (see figs. 2 and 4,) or the

same wire which forms the support b may be bent and coiled around the burner, as shown in figs. 3 and 5. Either can be readily removed, by slipping it up and off the burner B, or by opening the spring c.

The construction is simple, the finger being used within the circle, to give the fine wire, as it is being wound, the conical form. But, simple as it is, it is very useful, as well as economical, wherever gas is used or can be had in place of alcohol, or the equally dangerous and expensive spirit-gas, which is now commonly employed to produce a large flame, by means of a large and spreading wick, for soldering-purposes.

The cap, A, being attached to the burner B, and the gas ignited, the wires of which the former is composed, by intercepting the flame, spread it through the whole extent of the cap or cone A, while most of them become heated to redness, and thereby the whole of the gas issuing from the burner is consumed, and thus not only is the volume of flame increased, but the heat and the illuminating-effect are also increased.

Ordinarily, with the best simple burner, without some attachment or device for arresting the gas, much of it is lost or unconsumed, the heat generated, by the combination of the oxygen of the atmosphere with it, being insufficient, without arresting it, to consume the gas emitted.

The flame issuing from the exterior of the cone A is concentrated and directed, by the blow-pipe, as required, the same as the flame of the alcohol-lamp.

Claim.

What I claim as my invention, and desire to secure by Letters Patent of the United States, is—

The wire cone or cap, A, in combination with the support b and spring c, when constructed and employed substantially as and for the purpose set forth.

FREDK. SHALLER.
